SIPHON APPARATUS FOR FLUSH TANKS
 Paul E. Pihl, Bluemont, Va., and Preston M. Hall,
 9612 Merwood Lane, Silver Spring, Md.
 Filed Feb. 17, 1960, Ser. No. 9,218
 10 Claims. (Cl. 4—48)

This invention relates generally to liquid receptacle control means and more particularly to the flushing apparatus for flush tanks.

The primary object of this invention is to provide a simple inexpensive apparatus for a flush tank which eliminates the need for a gravity operated stop flow outlet valve, said valve being the cause of a large percentage of the leaky flush tanks. While a leaky flush tank connected to a municipal water distribution system is an expensive annoyance, a leaky flush tank connected to an independent supply such as a well or tank on a farm is intolerable as it will soon exhaust the water supply. In prior efforts to eliminate leaky flush tanks, various siphon tube arrangements have been proposed but none have been acceptable practically or commercially.

Siphon tubes used prior to this invention have several disadvantages, one being that they are usually of a fixed length and therefore are effective only for a certain given static water level, which in turn depends on a given constant water pressure. The device of the present invention, however, is adapted by a novel float means to function effectively at various water levels since the effective siphon tube is vertically extensible and the top of the tube is held at a fixed distance relative to the water level.

Another disadvantage of siphon tubes, particularly extensible tubes found in the prior art, is that they are too complex and therefore, inefficient, costly, and require special tank fittings. Moreover, they may require jetting to initiate the siphon action and to expel the contents of the tank through the discharge pipe, in some instances, requiring that the operator hold the handle during part or all of the flushing operation.

The relatively simple device of the preferred embodiment of this invention merely employs a float, discharge tube, and a flexible connection therebetween, and it is only necessary to depress the operating handle momentarily so as to initiate a siphon action. Moreover, the device may be easily installed by a "do it yourself" homeowner in any flush tank by a simple connection requiring no special skill or tools.

Accordingly, a further important object of this invention is to provide a siphon apparatus for a flush tank that may be quickly and easily installed in a conventional flush bulb operated flush tank to replace the latter means.

Another object of this invention is to provide an inexpensive apparatus which will efficiently empty a flush tank by a siphon means having controlled flow and relatively strong siphoning power.

Another object is to provide a flushing apparatus that may operate at varied water levels with the same high quality performance at each level.

Another object of the invention is to minimize the noise usually attending the operation of conventional flush tanks by instituting a quietly operating siphon action to effect discharge from a tank.

More specifically it is an object of this invention to provide a flush tank siphon apparatus embodying an upright open ended tube having an annular weir of uniform height over which water is carried to overflow to initiate siphoning action.

Further objects will be apparent to those skilled in the art from the following description of the apparatus and exemplifications thereof, and from the scope of the appended claims.

2

These and other objects are realized in the preferred embodiment of this invention by utilizing a siphon device featuring a vertically extensible siphon tube, a float cooperating with said siphon tube, and a flow restriction means located in the flush tank discharge tube.

In the drawings:

FIGURE 1 is a front view partially in section of the first embodiment of our invention;

FIGURE 1A shows the relative positions of the discharge pipe, flexible sleeve, and flow restriction means as and immediately after the liquid has been flushed from the tank;

FIGURE 2 is a sectional plan view taken along line 2—2 of FIGURE 1;

FIGURE 3 is a fragmentary vertical sectional view of the flow restriction means of the FIGURE 1 embodiment;

FIGURE 4 is a view of the lower end of the flush tank discharge tube showing a modified form of the flow restriction means;

FIGURE 5 is a sectional elevation view of another embodiment of the present invention;

FIGURE 5A is a fragmentary section along the line 5A—5A of FIGURE 5;

FIGURE 6 is a sectional elevation view of another embodiment of the present invention;

FIGURE 6A is a fragmentary section along the line 6A—6A of FIGURE 6;

FIGURE 7 is a view partly in sectional elevation of another embodiment of the present invention;

FIGURE 8 is a sectional elevation of the siphon pump shown in FIGURE 7;

FIGURE 9 is a horizontal sectional view taken along line 9—9 of FIGURE 8;

FIGURE 10 is a sectional view of still another embodiment of the present invention; and

FIGURE 11 is an enlarged view of a portion of FIGURE 10.

While the invention broadly may be used for dispensing any type of liquid in regulated amounts, the description will be restricted to its use in a flush tank for the purpose of illustrating this invention. FIGURE 1 shows a conventional ceramic flush tank 2 having a cover 4, and a water inlet fitting 6 which extends through the bottom of tank 2 which is water sealed thereto at 7 and which is connected to an inlet control valve 10 through pipe 8. Valve 10 is operated by a conventional float 12 on rod 14 and admits water to the bottom of the tank through a refill tube 16.

The siphon device of the present invention for discharging water from the tank comprises a substantially vertical, single column discharge pipe 17 extending vertically through a conventional tubular bulb valve seat element 18 in tank outlet opening 2' and fixed thereto by a water tight securing means 19, which is preferably a water resistant cement, a tightly fitting rubber ring, or other suitable water resistant material capable of securing pipe 17 in element 18 against relative movement. Valve seat element 18, which is exteriorly threaded is mounted in water tight relation through opening 2' by means of nut 20 and gaskets 20' and the lower end of valve seat element 18 extends through the opening 21' in the upper portion of a flush bowl 21 and is extensively sealed thereto in the conventional manner. With the exception of pipe 17 and securing means 19, the structure thus far described is conventional and further details will therefore not be set out. The discharge pipe 17 extends substantially concentrically through flush valve seat element 18 and is substantially longer than said valve seat element 18 for a purpose to be described hereinafter. Surrounding the upper portion of pipe 17 in the tank 2 is a flexible sleeve 24 which is made of latex, neoprene, nylon or other suitable water resistant highly flexible material and at its

50

55

60

65

70

lower end is sealingly clamped to pipe 17 by a friction clamp ring 25.

An inverted cup-shaped siphon bell 30, which may be of either light metal or plastic, has in this embodiment four substantially concentric tubular members depending from the top wall 39 thereof. Skirts 35 and 38, the outer and next inner members respectively, are sealingly secured to or integral with the under surface of top wall 39 of the float, skirt 36 being substantially longer than 38. When the water surface seals the annular bottom opening of the annular space 37 between skirts 36 and 38 as shown at 37' in FIGURE 1, the annular space 37 with air entrapped therein forms an annular float chamber in bell 30. Flotation may be effected by means of sealed air pockets, plastic foam, rubber foam or any other similar means providing sufficient buoyancy to place the top edge 44 of a tubular member 40 (about to be described) above water level 39' of the water between skirt 38 and tubular member 40 which is the same level as the level of the water in the tank 2 outside skirt 36.

Also suspended from the top wall 39 of the bell 30 is the tubular member 40 having its upper edge 44 spaced from said top 39 and a lower portion closely surrounding the outwardly flared upper lip 17' of discharge pipe 17 to cooperate therewith to guide the vertical movement of bell 30 within tank 2 and receiving the upper end of sleeve 24 at 28 as shown. In its unstretched condition, the internal diameter of sleeve 24 is less than the external diameter of tubular member 40 so that when it is stretched over the lower end of tubular member 40, it forms a fluid tight seal therewith. The internal diameter of sleeve 24 is, however, greater than the external diameter of tube 17 within tank 2 being normally held against the exterior of pipe 17 by exteriorally applied hydrostatic pressure of the water within tank 2.

Innermost depending member 46 which constitutes a combined flow restriction means and secondary water inlet also depends from the top wall 39 and surrounds an opening 47 in the top wall 39 of the bell 30. The portion 48 of wall 39 defining opening 47 is funnel shaped while the lower portion of tube 46 has a radially outwardly extending annular flange 52 the periphery of which is substantially uniformly spaced from the interior of tube 17 when the apparatus is in the position shown in FIGURE 1.

Disposed above the funnel portion 48 of wall 39 is another water inlet pipe 56 which is also connected to inlet valve 10 and controlled by float 12.

The overall horizontal cross-sectional shape of the bell may be cylindrical, rectangular, elliptical or irregular so long as the minimum cross-sectional area of the upward flow passage within the siphon bell 30 around tube 40 is equal to or greater than the minimum cross-sectional area of the outward flow passage through the discharge tubes 40 and 17. In other words, as will be seen from the FIGURES 5 and 6 embodiments, the bell may be elliptical or rectangular rather than cylindrical as shown in FIGURES 1 and 2. The optimum configuration of bell 30 is dictated by the tank design. The primary consideration is to provide enough area around tube 40 for water flow up to the top edge 44 of the tube 40 and down into the tube 40 so that there will be no restriction in volume.

In operation of the device, handle 58 is actuated and causes an actuator bar 60 to depress siphon bell 30 a distance vertically downward at least sufficient to lower the upper edge 44 of tube 40 below the water level 39' to thereby initiate a siphon action. The depression of the bell 30 causes water to flow over edge 44 carrying with it the small amount of air trapped inside member 38 above the water level 39' and quickly filling 17.

Because the discharge pipe 17 has a long lower portion which extends through valve seat element 18, a large water head is built up therein when the bell 30 is depressed thereby producing a stronger siphon action than is found

in prior siphoning devices used for this purpose. Not only does the extra length of this pipe produce a stronger siphon, it also enables the siphon action to be initiated instantly by a depression of the handle since this lower portion of the tube acts in cooperation with flow restriction means 52 as shown in FIGURE 1, or in the alternative, flow restriction means 64 shown in FIGURE 4 (both of which are hereinafter described) to build up the head rapidly. This rapid build-up insures that the siphon will not be broken by offsetting any sudden buoyancy effect which might result when the operating handle 58 is suddenly released. When siphoning action is established, the pressure within skirt 38 above the top of tube 40 drops below atmospheric pressure sufficiently so that the siphon float 30 and hence tubular member 40 will also be lowered around pipe 17 to the bottom of the tank 2 and will remain there until after the tank is substantially emptied and the siphon is broken by air flowing in below the bottom of skirt 36 at which time water inlet valve 10 controlled by float 12 begins to refill the tank in a well-known manner. The bell 30 will remain on the bottom until flotation is established at which time the bell 30 will float and support the lip 44 above the level of the water as the tank is filled. For example, the buoyancy should be such that lip 44 is supported approximately $\frac{3}{8}$ " above the water level. This assures prevention of leakage but permits overflow over lip 44 if the shut-off valve should not function after sleeve 24 has reached its fully extended position. This overflow action takes place without initiating siphoning action as the overflow rate is very slow.

Of particular importance in the operation is the character of sleeve 24 which must offer very little upward force after being depressed. Otherwise, the bell 30 would be prematurely raised to the top position and stop the siphoning action. Therefore the sleeve 24, in addition to being made of light flexible rubber which is preferably no heavier than that used in surgical gloves, for example, is also arranged to fold, slip down, or roll back over on itself as tubular member 40 is lowered. This "roll back" characteristic, illustrated in FIGURE 1A, results in practically no resistance due to folding or kinking. There is substantially no appreciable friction between tubular member 40 and the rubber sleeve 24 or between different portions of the rubber sleeve 24 itself inasmuch as water is an excellent lubricant for rubber. While, to insure that the sleeve 24 rolls back on itself, an inverted frusto-conical shape sleeve element may be used, the sleeve 24 shown in FIGURE 1 has been found to be inexpensive and very efficient.

As long as valve 10 is open, tube 56 directs a small stream of water through funnel portion 48 and tube 46 and thence into a closet bowl so as to provide the required water seal. This water inlet arrangement of my invention is efficient and economical inasmuch as it is not necessary to provide a special inlet tube into pipe 17 as is commonly done.

When water is flushed from a tank through a discharge pipe there will be a flow pattern established in the tube. This invention utilizes a radially outwardly extending annular flange 52, which constitutes the flow restriction means of this invention, on the water inlet tube 46 which effectively blocks passage of air through the center of the tube 17 while it permits the flow of liquid between it and the pipe 17. The purpose of the flow restriction means is to reduce the cross-sectional area of the tube 17 at least when operation is initiated sufficiently so that a minimum amount of water overflowing the top edge 44 of tube 40 will form a slug of water providing a seal transversely of the tube 17 and thereby prevent air flow through the tube 17, which in turn would prevent initiation of the siphoning action. Thus the flow restriction means performs a dual function since it also allows the siphon to be initiated with only a momentary depression of the float, as brought out above, by restrict-

ing the flow area in the discharge pipe 17 to cause a quick build-up of water therein and thereby prevent the slight rebounding, due to buoyancy, of the float 30 from breaking the siphon prematurely.

The flow restriction means is shown in the preferred form on tube 46 in FIGURES 1 and 1A, since this form cause a flow restriction while the float is being lowered but it also provides unrestricted flow after the element 52 passes the lower extremity of pipe 17 as soon as the siphon has been initiated. It is within the scope of this invention to suspend a disk-like member similar to element 52 by means of a spider or other support in the pipe 17.

FIGURE 4 shows another flow restriction means 64 which is a radially inwardly extending annular flange 64 in pipe 17, that may be substituted for element 52. Flange 64 restricts the flow at the bottom of the pipe to a narrow vortex so as to eliminate the possibility of an air pass in the center thereof and also provides for a water build-up in the discharge pipe as does element 52 but, being fixed in tube 18, results in a slower rate of total evacuation of tank 2.

The embodiment of FIGURES 5 and 5A comprises a vertically extensible tube assembly 70 formed by an inner rigid tube 72, an outer rigid tube 74 slideably interfitting with the tube 72, and a sleeve-type flexible bellows 76 fixed in fluid tight relation to the lower end of tube 72 by a collar 78 and fixed in fluid tight relation at its upper end to the exterior of tube 74 substantially midway of its length. The lower end of tube 72 is fixed in fluid tight relation to the outlet fitting 80, of conventional form extending through the discharge opening 82 of the bottom wall of the tank 84. A guide collar 86 is provided on the exterior of the lower end of tube 74 to prevent the thin wall rubber bellows 76 from wedging between the tube 74 and 72 under the influence of the externally applied hydrostatic pressure as the tube 74 is lowered relative to the tube 72. The bell 88 comprises an inverted cup-shape element 90 of elliptical cross-section horizontally, as is best shown in FIGURE 5A, having transverse partitions 92 and 94 defining with the opposite ends of element 90 open bottom air pockets 96 and 98. The bell 88 is mounted upon the upper end of the tube 74 by joining the external surface of tube 74 to the opposed surfaces of the partitions 92 and 94 in substantially line contact as by cementing along the lines 100 and 102. By this construction, the air trapped within the compartments 96 and 98 above the level of the water at the bottom thereof indicated at 104 and 106 buoyantly supports the bell 88 and the tube 74 so that the overflow weir defining top edge 108 of the tube 74 is normally supported slightly above the level 110 of the water within the cup-shaped element 90 between partitions 92 and 94 which level is the same as the level 112 of the water outside the bell 88. When the bell 88 is depressed by a suitable mechanism similar to that illustrated in FIGURE 1 so that the edge 108 is below the level 110, water is free to flow upwardly around the tube 74 between the partitions 92 and 94, over the top edge 108 and down through the tube 74 and the tube 72 to the discharge. The overflow of edge 108 is preferably uniformly distributed circumferentially around edge 108. As in the previous embodiment, a suitable flow restriction means is preferably fixed to the lower end of the secondary water inlet conduit 114 suspended from the top wall of the cup-shaped element 90. As soon as siphon action is initiated, the air trapped between partitions 92 and 94 above the level 110 of the water will be evacuated through the tubes 72 and 74 and the bell, due to the difference in pressure exerted on the exterior of its top surface and the interior of its top surface between partitions 92 and 94, will rapidly drop its lower position in which its lower edge 115 rests on the bottom of the tank 84. A recess or opening 118 is formed through the side wall of the cup-shaped element 90 at each side to permit continued

flow of liquid from the tank through the recess 118 and upwardly through the interior of the cup-shaped element 90 to overflow the top edge 108 of the tube 74. Flow will continue until the level in the tank reaches the level 5 of the top edge of recess 118 when the cup-shaped element 90 is in its lower position with its bottom edge 116 resting on the bottom of the tank 84. When the water reaches that level, air will be drawn in through the recess 118 and siphon action broken. Refilling of the tank with 10 this embodiment is in all material respects the same as in the previous embodiment.

The embodiment of FIGURES 6 and 6A is similar to the embodiment of FIGURES 5 and 5A with the exceptions that a bell 130 of rectangular cross-section is 15 provided as is shown in FIGURE 6A and a substantially frictionless water tight joint 132 is provided between the inner tubular member 134 and the outer tubular member 136 of the axially extensible siphon tube assembly 138 in lieu of the bellows 76 of the FIGURES 20 5 and 5A embodiment. The bell 130 is formed by an inverted cup-shaped element 140 of rectangular horizontal cross-section and is provided with transverse partitions 142 and 144 defining with the cup-shaped element 140 air pockets 146 and 148 which are open at their 25 lower end and which form float chambers. The bell 130 is fixed to the top of the tube 136 with its top wall 150 in vertically spaced relation to the top edge 152 of the tube 136 by equally angularly spaced struts 154 which permit free circumferentially uniform flow of water over 30 the annular weir defining top edge 152 when the bell 130 is depressed sufficiently to lower the top edge 152 below the normal level 156 of the water within the cup-shaped element 140 between the partitions 142 and 144. The normal level of the water within the tank around the bell 35 130 is indicated at 158 and the normal level of the water within the compartments 146 and 148 is indicated at 160 and 162. The water tight frictionless joint 132 between the tubular members 134 and 136 is provided by a body of liquid 164 retained in the open top sealed bottom 40 annular space between the tube 134 and a further tube 166 which is in radially spaced surrounding relation to the tube 134 and between which the tube 136 is free to move vertically. The body of liquid 164 is preferably of mercury but may be of any other fluid which is heavier 45 than the liquid contained within the tank, which will not wet or adhere to the tube 136, which is non-corrosive, which is immiscible with and insoluble in the liquid within the tank. Since mercury meets all of these conditions, it is ideally suitable for use in a flush tank; the sole disadvantage being the expense on the present day market of mercury in sufficient quantities. The proportions of 50 the annular space between the tubes 134 and 136 and the lengths of the tubes 134, 136 and 166 are such that the lower end of the tube 136 is immersed within the body of liquid 164 when the bell 130 is in its upper position as shown in FIGURE 6 and the tube 136 may be lowered fully into the body of liquid 164 without causing that liquid to overflow the tops of the tubes 134 or 166. By this construction, the tubes 134, 136 and 166 provide 55 a vertically extensible siphon tube offering substantially no resistance to the descent of the bell 130 and no upward force upon the tube 136 tending to force it upwardly and prematurely break the siphoning action. With these exceptions, the operation of this embodiment is substantially identical with that of the preceding embodiments described above in detail.

FIGURES 7-9 show still another modification of the present invention. Discharge pipe 183 has secured at the upper end thereof a support bracket 184 which rotatably supports an open end cylindrical pump element 186 by means of a pivot pin 188 secured to said bracket. The pump is spaced evenly from pipe 183 by means of spacers 191 which are secured to said pipe and have a ball-shaped end to reduce friction.

75 On the inner wall of the pump is mounted a plurality

of spiral-shaped vanes 190. On the outer wall is a continuous spiral groove 192 adapted to receive follower element 194 mounted on actuator rod 196.

In operation the actuator rod is depressed causing the pump to rotate by moving the follower 194 through slot 192 to the bottom thereof. Rotation of the pump element causes water to rise and flow into the discharge pipe due to the action of the spiral vanes and a siphon is thereby initiated. Once rod 196 has been depressed and the handle released by the operator, spring 193 will bring it back to its initial position at about the same time the tank is refilled by the conventional float and water inlet means (not shown).

This form differs from above embodiments in general operative principle in only one respect, i.e., instead of lowering the discharge pipe to the water, the water is raised to said pipe to initiate the siphon; and while this slight difference exists, this modification may still be used with varying water levels since the pump is partially filled with liquid at all times as shown in FIGURE 7 when the tank is full.

In FIGURES 10 and 11, another modification is shown which employs a float (not shown) having a tubular member 199 similarly as shown in FIGURES 1, 5 and 6. The upper portion of discharge pipe 201 has an annular groove 200 which receives a rubber O-ring 204. Mounted around O-ring 204 is an annular Teflon sealing ring 208 which has an annular depression 210 for engaging said O-ring 204 and preventing relative vertical movement therebetween. The side of the Teflon ring 208 opposite depression 210 fits flush against tubular member 199.

In operation the float is depressed and a siphon is initiated as described in the operation of FIGURE 1. The water being discharged by downward flow through tube 199 and pipe 201 is prevented from flowing through the annular space between the lower portion of tube 199 and pipe 201 by O-ring 204 and the Teflon ring 208, but due to the lubricating effect which the water has on the Teflon virtually no friction is encountered by tube 199 on ring 208 and the float subsides with the water level uninhibited.

The sealing rings 204, 208 also act as guide elements for tube 199 assuring vertical descent of float.

All embodiments of the present invention can be used in liquid vending or dispensing machines delivering a measured or unmeasured amount of liquid, or slurry, or of a liquid having small suspended particles such as is common in fruit beverages and the like.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In combination with a liquid receptacle having a bottom outlet opening open externally of said tank to atmosphere, a fluid flow outlet apparatus comprising a tubular fluid outlet conduit vertically disposed in said receptacle and having an open top and its lower end internally disposed to provide fluid communication with said receptacle outlet opening and externally connected in fluid tight relation thereto to prevent fluid flow from said receptacle other than through said conduit, an inverted cup-shaped element attached to said conduit for vertical reciprocating movement relative to said receptacle in a predetermined path between a normal elevated position and an operated depressed position and having a top end wall disposed in spaced relation to the top end of said conduit to permit fluid to pass between the upper end of said conduit and

the top end wall of said element, said element having a depending continuous side wall extending from said element end wall downwardly in spaced surrounding relation to the upper end portion of said conduit to define a flow passage with the exterior of said conduit, manually actuatable means for actuating said element from its normal toward its operated position, and means in said conduit operative at least during initiation of flow through said conduit to restrict the cross section of said conduit to assure formation of a water seal across said conduit during initiation of water flow through said conduit.

2. The combination defined in claim 1 wherein said conduit is provided with means intermediate the ends thereof permitting relative axial converging and diverging movement of the ends thereof, wherein said element is fixed to the upper end of said conduit.

3. The combination defined in claim 2 wherein said conduit comprises a pair of telescopically interfiting rigid tubular members interconnected at their overlapping ends by a thin highly flexibly tubular sleeve.

4. The combination defined in claim 2 wherein said conduit comprises a pair of telescopically interfiting rigid tubular members and wherein said movement permitting means comprises a liquid joint provided with a liquid which is immiscible and insoluble in water, which is non-wetting, and which has a specific gravity greater than one.

5. The combination defined in claim 4 wherein the liquid of said joint is mercury.

6. The combination defined in claim 2 wherein the said conduit comprises a pair of tubular rigid members arranged in coaxial relation and wherein said movement permitting means comprises a highly flexible bellows interconnecting the adjacent ends of said tubular members.

7. The combination defined in claim 2 wherein said conduit comprises a pair of telescopically interfiting tubular members and wherein said movement permitting means comprises concentrically arranged sealing structure interposed between the opposed surfaces of said members embodying an O-ring fixed to one of the said opposed surfaces and a Teflon ring interposed between said O-ring and the other of said opposed surfaces, said Teflon ring being fixed to said O-ring and in sliding sealing contact with said other opposed surface.

8. The combination defined in claim 1 wherein said conduit extends through said receptacle outlet opening to a position substantially below the bottom of said tank so that fluid discharged through said conduit from said receptacle is confined within said conduit to a level substantially below the bottom of said tank to provide a substantial pressure differential to maintain proper siphoning action.

9. The combination defined in claim 1 wherein said restricting means comprises a flow restricting element disposed in said conduit and movable with said element from a flow restricting position when said element is in its said normal position to an inoperative position when said element is in its operative position.

10. The combination defined in claim 1 wherein said flow restricting element comprises a disk disposed transversely of said conduit and suspended from said element end wall concentrically in said conduit.
